Patented May 12, 1959

185,166

SPRING ACTUATED RAZOR

Georges Monnet, New York, N.Y.

Application March 5, 1957, Serial No. 45,116

Term of patent 3½ years

(Cl. D22—3)

Fig. 1

Fig. 2

Fig. 4

Fig. 3

Fig. 1 is a side elevational view of a spring actuated razor, showing my new design;

Fig. 2 is a front elevational view thereof;

Fig. 3 is an elevational view showing the side opposite to that of Fig. 1; and

Fig. 4 is a rear elevational view thereof.

I claim:

The ornamental design for a spring actuated razor, as shown.
